UNITED STATES PATENT OFFICE

FRED KLIM, OF MORRISTOWN, NEW JERSEY

WINDOW

Application filed March 17, 1930. Serial No. 436,609.

The present invention relates to windows and more particularly to the rear windows of automobiles and other motor driven vehicles and has for its primary object to provide a swinging support for the window together with operating means for moving the same into open and closed position whereby to provide ventilation through the rear window of the vehicle.

10 A further object is to provide a novel operating mechanism for the window providing for its movement into open and closed position with minimum effort and which at the same time is strong and durable, efficient 55 and reliable in performance, relatively inexpensive to manufacture and install in operative position in the vehicle and otherwise well adapted for the purposes for which the same is intended.

20 Other objects and advantages reside in the special construction, combination and arrangement of the various elements forming the invention as more fully hereinafter described and claimed, reference being had to the accompanying drawings forming part hereof wherein like numerals refer to like parts throughout, and in which:

Figure 1 is a view in elevation showing the outside of the window,

30 Figure 2 is a similar view of the inside of the window,

Figure 3 is a vertical transverse sectional view,

35 Figure 4 is a fragmentary vertical section- al view taken substantially on a line 4—4 of Figure 2,

Figure 5 is a fragmentary sectional view through one of the pivoted supports for the window,

40 Figure 6 is a fragmentary sectional view taken substantially along a line 6—6 of Figure 2, and

Figure 7 is a similar view taken substantial- 45 ly along a line 7—7 of Figure 2.

Referring now to the drawings in detail for the purpose of illustration I have disclosed a preferred embodiment of the invention mounted in position within an automobile 50 body indicated generally at 5, the window 6

being positioned within the window opening 7 at the back of the body.

At the vertical side edges of the window guard strips 8 are provided forming a covering about the edges of the window and within 55 which the window is secured, as by means of cement or the like to prevent the separation of the window from the strip.

Within the sides 9 of the window opening is fitted bushings 10 providing bearings for trunnions 11 to one end of which U-shaped plates 12 are formed extending inwardly of the window opening for attaching to the opposite sides of the guard strip 8 by rivets 13 or the like. To the opposite end of the trunnions links 14 are fixedly secured extending at right angles to the trunnions and with their free ends bifurcated as shown at 15.

Within the bifurcated ends of each of the links are pivoted rack bars 16 slidable in guides 17 secured to the wall of the body. The rack bars at the opposite ends of the window extend uniformly as clearly shown in Figure 2 of the drawings and are oper- 75 atively engaged by spur gears 18 carried at the opposite end of a shaft 19 extending trans- versely of the body above the upper edge of the window and journaled in supports 20 se- cured to the body of the vehicle.

A beveled gear 21 is attached to the shaft 80 intermediate its ends with which a pinion gear 22 is engaged, said pinion gear being keyed to a shaft 23 journaled in the body of the car and extending forwardly into the in- 85 terior of the car above the window opening and provided with an operating handle 24.

It will be apparent from the foregoing that upon the manipulation of the handle 24, that the rack bar 16 will be moved vertically and through its connection with the trunnion 11 90 will cause the window 6 to swing upon said trunnion.

The bottom edge of the window opening along its inner side is provided with an up- 95 standing beading 25 against which the lower edge of the window may abut to prevent the swinging of the lower edge of the window in- wardly and the upper edge of the window opening at its outer side is provided with a similar beading 26 to engage the upper edge 100

of the window to prevent the outward swinging of the upper edge thereof.

It will be noticed that the window attaching plates 12 are positioned adjacent the upper edge of the window so that a relative slight movement of the handle 24 will cause the lower edge of the window to swing outwardly the desired extent.

By forming the beadings 25 and 26 oppositely at the lower end upper edges of the window opening a weather tight fit is provided for the window.

It is obvious that my invention is susceptible to various changes and modifications in construction without departing from the spirit of the invention or the scope of the appended claim, and I accordingly claim all such forms of the device to which I am entitled.

Having thus described my invention, what I claim as new is:

In combination, a vehicle body having a window opening, a window fitted in the opening, metallic channel members secured on the vertical marginal portions of the window, U-shaped members secured on the channel members, bearings in the vertical sides of the window opening, trunnions on the U-shaped members journaled in the bearings, arms fixed on the free ends of the trunnions, upstanding rack bars pivotally connected to the free ends of the arms, a shaft journaled horizontally in the body above the window opening, gears fixed on the ends of the shaft and meshed with the rack bars, channeled guides mounted in the body and slidably engaged with the rack bars for maintaining said rack bars in operative engagement with the gears, a shaft journaled in the body adjacent the first named shaft and at right angles thereto, gears operatively connecting the shafts together, and means on the second named shaft for manually actuating same.

In testimony whereof I affix my signature.

FRED KLIM.
